UNITED STATES PATENT OFFICE.

SAMUEL RAWSON, OF PEORIA, ILLINOIS.

HEN-HOUSE.

SPECIFICATION forming part of Letters Patent No. 289,307, dated November 27, 1883.

Application filed May 12, 1883. (Model.)

To all whom it may concern:

Be it known that I, SAMUEL RAWSON, a citizen of the United States, residing at Peoria, in the county of Peoria and State of Illinois, have invented certain new and useful Improvements in Hen-Houses; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a top view of the device with the upper board removed, illustrating this invention. Fig. 2 is a cross-section of the same, taken on lines *x x* of Fig. 1. Fig. 3 is a front view, and Fig. 4 is an end view.

This invention has relation to automatically opening and closing boxes adapted to contain the nests of hens, geese, and other fowls; and the invention consists in the construction and novel arrangement of devices, all as hereininafter set forth.

In the accompanying drawings, the letter *A* designates the box, which is usually made rectangular in form.

B and *C* indicate the side walls of the box, and *D* the front wall, having the doorway *E*.

F represents the door, which is hinged at the side of the doorway, and is usually constructed of strips or bars having intervals between them, to afford light to the passage-way back of the door. The door is provided with a movable shutter-grate, *G*, which can be operated to close the openings *a* in the door when desired.

From the front wall of the box extends, toward the rear thereof, a partition, *H*, the rear end of which is separated from the rear wall of the box by an interval, *b*, of sufficient size to allow the hen to pass by the rear end of the partition to the nest-chamber, which is located on the other side thereof.

K represents the nest, which is usually separated from the rear aisle, *L*, by a vertical board, *b'*, of sufficient height to prevent the escape of a very young chicken from the nest; or the board *b* may be made lower, if thought preferable. The nest may be raised above the floor of the box.

The top of the box above the passage-way back of the door is permanently secured, as indicated at *c*, and to this portion is hinged 55 the cover *d* of the nest-chamber, which may be fastened down by means of a hook and staple or other common fastening.

Below the cover *d* is located the ventilator-cover *e*, which is constructed with air-openings, and rests upon interior ledges. This interior ventilator-cover is removable, and, when in place, is secured by means of pivoted hooks *h* at the corners of the box. The ventilator-cover is used in summer-time, the hinged 65 top *d* being thrown open and resting on the fixed portion *c*.

In the partition *H* is made an opening, *k*, which may be partially or wholly closed by means of a sliding shutter, *l*.

On the front wall is provided a movable window-sash, *f*, having a glazed opening and designed to close the opening *m*. The sash *f* works in guideways *n*. The side wall of the nest-chamber at the end of the aisle is also provided with a window, *p*, which should be glazed.

At the upper and middle portion of the partition *H* is pivoted an arm or lever, *N*, which projects transversely over the passage-way *M*, 80 in the bottom portion of which passage-way is located the tilting treadle *T*, which is pivoted at its middle portion above the floor of the passage, and forms the bearing on which the hen or other fowl walks in moving along said 85 passage.

P indicates a coupling, which is pivoted to a projection, *r*, at the top of the door, and, extending back, is pivoted at its rear end to the lever-arm, *N*.

To the rear end of the treadle is connected, at one corner thereof, a cord, *s*, which extends upward over a corner pulley or bearing, *t*, and around a horizontal pulley or bearing, *v*, to the lever-arm *N*. This arm is provided with a rounded bearing, *w*, and with a key, *z*, to which the end of the cord *s* is attached, said cord passing around the bearing *w*. The cord may be tightened or loosened by turning the key. A similar key, *z'*, is provided in the 105 arm *N* for the cord *s'*, which passes around the bearing *w* in the opposite direction to a corner pulley, *t'*, whence it descends to the front end of the treadle, to which it is attached. The

cords s and s' are usually adjusted with equal tension, so that when the door is open the front end of the treadle will be depressed and the rear end raised, the lever-arm N being at 5 the same time inclined obliquely forward. When the door is closed, the rear end of the treadle will be depressed and the front end raised, the lever-arm being pulled backward. The treadle and door should be made of proper 10 weight and size for the fowl which is to use the nest. The door being open, the fowl enters upon the treadle, and, walking to the rear end of it, bears it down by its weight at this end, operating the lever-arm to close the door. 15 The fowl can now go on the nest without being disturbed. When she desires to leave the box, she can only get out by crossing the treadle to the front end, or the reverse of the direction in which she entered, causing it to descend, whereby the door is opened through 20 the operation of the cord s' and the lever-arm. If desired, the cord s' may be loosened, so that the operation of the treadle will close the door, but will not open it. If, on the other hand, 25 the cord s is loosened, the cord s' being adjusted as before, the treadle, when operated, will open the door, but will not close it.

The box is usually provided with an automatic latch, V , designed to engage a projection or catch, R , on the door. The latch is 30 provided with a pivoted prop, a' , which can be set to hold the latch up out of engagement. When it is desired to compel the fowl to remain in the box, the prop is turned off, so that the latch will operate. In this manner a 35 convenient trap is provided whereby a hen can be caught in a few minutes.

Having described this invention, what I claim, and desire to secure by Letters Patent, is—

The device for automatically closing and opening the door, consisting of the treadle T , pulleys t , v , w , and t' , the hinged arms N and P , and the cord s , attached at its respective ends to opposite ends of the tilting treadle and carried around the said pulleys, which are located above the entrance-passage, substantially as specified.

In testimony whereof I affix my signature in presence of two witnesses.

SAMUEL RAWSON.
